UNITED STATES PATENT OFFICE.

GEORGES PHILIPPE OMER HÉROUX, OF THREE RIVERS, CANADA, ASSIGNOR
TO JOSEPH TELESPHORE LORD, OF WOONSOCKET, RHODE ISLAND.

BAG.

SPECIFICATION forming part of Letters Patent No. 686,899, dated November 19, 1901.

Application filed June 22, 1901. Serial No. 65,548. (No model.)

To all whom it may concern:

Be it known that I, GEORGES PHILIPPE OMER HÉROUX, a subject of His Majesty the King of Great Britain, residing at Three Rivers, county of St. Maurice, Province of Quebec, Canada, have invented certain new and useful Improvements in Bags; and I do hereby declare that the following is a full, clear, and exact description of the invention, such as will enable others skilled in the art to which it appertains to make and use the same.

My invention relates to improvements in bags, the same relating more especially to paper-bags, although the improvement may be used in connection with fabric bags or with analogous devices which it is desired to quickly and securely close.

The object of the invention is to provide means which will save the time, labor, and cord or twine usually consumed by merchants and others in tying up bags, thus providing a substitute by which the bag-mouth may be securely and quickly closed. The improved fastener forms a part of the bag, because it is made and applied at the period of manufacture of the bag, which is sold as a complete article, and such improvement is very simple and cheap, so that it does not materially increase the cost of manufacture.

With these ends in view the invention consists in the novel construction and arrangement of parts, which will be hereinafter fully described and claimed.

In the drawings hereto annexed, forming a part of this specification, Figure 1 is a perspective view of a part of a paper bag equipped with a metallic fastener of my invention. Fig. 2 is a vertical cross-section thereof. Fig. 3 is a side elevation of the bag in its open condition in order to show the relative arrangement of the members of the fastener before the bag is closed. Fig. 4 is a side view showing the bag in a partially-closed condition. Fig. 5 is a top plan view of the bag closed and secured by the fastener of my invention.

The same numerals of reference denote like parts in each of the several figures of the drawings.

5 designates the bag, which may be made of paper, fabric, or any other suitable material,

and this bag may be of any desired size and of any appropriate shape.

The improvement in the present case resides in a metallic fastening means which is applied to the bag at the period of its manufacture and which forms an integral and inseparable part thereof, the whole forming a complete article adapted to be placed on the market and sold to merchants or others for use in their business in packaging merchandise. 55 The improved fastener consists of two members 6 7, the same applied to opposite sides 8 9 of the bag. These members are disposed in parallel relation on the opposite sides of the bag, and they are arranged at different 65 distances from the open mouth thereof, so that one fastener member occupies a disaligned relation to the other fastener member. Each member of the fastener consists of a pliable strip of metal, which is housed or contained within a suitable sheath, (indicated in the drawings by the numeral 10.) I may form the metallic part of each fastener member from a single piece of ductile metal—such, for example, as wire, which is adapted to be 75 easily and quickly bent and which will remain in such bent condition; but I do not limit myself to the employment of this particular material, because it is evident that a strip of ductile metal may be employed in lieu 80 of the wire. The ductile strip is housed or contained within the sheath by doubling or folding the latter around the strip, (see Fig. 2,) and the free edges of the sheath are united 85 together in any suitable way—as, for example, by cementing them one to the other. The sheath of each member may consist of paper, a fabric, or any other appropriate material, and said sheath is united to the outside of the bag 5 in any approved way—as, for example, by cementing the parts together. Of course it is to be understood that the edges of the sheath may be united together and the sheath itself may be attached to the bag by 90 other means than by cementing the parts. 95

The member 7 and its sheath are fastened to the side 9 of the bag, near the top edge thereof, whereas the member 6 and its sheath are attached to the other side 8 of the bag some distance below the top edge. (See Figs. 2 and 100

3.) The fastener members are somewhat longer than the bag is wide, and hence the end portions of these members project beyond the sides of the bag, preferably for equal distances, as shown by Figs. 1 to 4, inclusive.

In using my invention the bag is opened to the condition shown by Figs. 1 and 2, and the fastener members are thereby separated, so that they will lie on opposite sides of the mouth, and thus permit the merchandise to be easily introduced into the bag and without any hindrance from the members of the fastener. After the desired quantity of material has been deposited in the bag the sides 8 15 9 are drawn together, so as to bring the two members 6 and 7 of the fastener into quite close relation, substantially as represented by Fig. 3. The bag-mouth having been closed, the top edge of said bag and the fastener member 7 are turned or folded over the side 8 of the bag in order to bring the member 7 into close relation and immediately alongside of the member 6, substantially as represented by Fig. 4. The unoccupied top portion of the bag may now be rolled upon itself one or more times in order to take up the surplus amount of material in the bag and to bring the members of the fastener within the rolled portion of the bag-mouth; but these members 6 7 are 30 not wholly housed within the bag, because the ends of said members project beyond the bag, as shown by the drawings. The operation of rolling the bag-mouth in the manner described serves to effectually close the article, and in order to secure the bag in this condition it is only necessary for the operator to bend the projecting end portions of the fastener members in opposite directions and upon the rolled mouth of the bag, as clearly 35 40 shown by Fig. 5. As the bent ends of the fas-

tener members will retain their positions, owing to the presence of the ductile metal in the sheaths of the members, it is evident that the rolled bag-mouth cannot accidentally open of its own accord, and hence the bag will be securely closed. 45

From the foregoing description, taken in connection with the drawings, it will be seen that the improved fastener means does not in any way interfere with the ordinary usage 50 of the bag. Such fastener is extremely cheap in construction, and the bag can thus be manufactured without appreciable increase in the cost, because machinery can be adapted to produce and assemble the parts of the bag 55 in the required position.

Having thus described my invention, what I claim as new is—

As a new article of manufacture, a bag provided with an attached fastener forming an inseparable part thereof, said fastener consisting of straight members secured to opposite sides of the bag and extending continuously across the same, one fastener member lying at the edge of the bag-mouth and the other fastener member arranged below the plane of, and parallel to, the first-named member both members having the end portions thereof extended beyond the edges of the bag and said extended ends of the members adapted to be bent backwardly and around a folded portion of the bag-mouth, substantially as described. 60 65 70

In witness whereof I have hereunto set my hand in the presence of two witnesses.

GEORGES PHILIPPE OMER HÉROUX.
